UNITED STATES PATENT OFFICE

2,326,664

HATCH VENTILATOR FOR REFRIGERATOR CARS

John S. Lundvall, Chicago, Ill., assignor to Union Asbestos & Rubber Company, Chicago, Ill., a corporation of Illinois

Application September 7, 1940, Serial No. 355,754

3 Claims. (Cl. 98—6)

This invention relates to a hatch ventilator for refrigerator cars and has for its object to provide an improved hatch ventilator for refrigerator cars equipped with convertible bulkheads by which such cars when converted from ice refrigerated cars into ventilated cars may be adequately ventilated without exposing the lading to damage from rain or dirt which may enter the cars through the open hatches. This invention is an improvement upon the convertible bulkhead for refrigerator cars covered by my pending application Serial No. 316,708 now Patent No. 2,238,700.

Most refrigerator cars are used intermittently as refrigerator cars in which the lading is cooled with a quantity of ice loaded into ice bunkers at one end or both ends of the car, and intermittently as ventilated cars in which the lading is ventilated by a stream of air inducted into the car through hatches in the car roof at one end of the car and emitted through other hatches at the other end of the car after circulation through the car lading. Some refrigerator cars are used as much as three-fourths of the time as ventilated cars.

Collapsible ice bunkers have been devised which can be collapsed to render most of the space occupied by the bunkers available for cargo and thus to increase the portion of the car available for lading when no ice is required. When the car is used as a ventilated car and the space beneath the open hatches employed for cargo, the cargo must be protected against damage from rain or air-borne dirt which may enter the car through the hatches.

An object of this invention is to provide a hatch ventilator which will protect the lading of the car from damage by rain and dirt without interfering with the circulation of the air required to ventilate the car.

A further object of the invention is to provide a hatch ventilator for refrigerator cars which can be made a part of the convertible bulkhead of a refrigerator car, which can be placed into operating position without the use of tools and when collapsed will so intermesh with the other structural units of the ice bunker as to render the entire capacity of the ice bunker available for its ice load.

A further object of the invention is to provide a hatch ventilator which is so designed that when collapsed against the car wall it will provide a duct along the car wall for the passage of air currents, and when extended or collapsed will leave no structural members to interfere with

the ready use of the car for lading or for its ice load.

A further object of the invention is to provide a hatch ventilator which will provide a pilfer-proof enclosure so as to render the car an efficient and safe car when used as a ventilated car without ice refrigeration, and which, when in collapsed position, will form a perforate wall for the collapsible ice bunker to form ducts which separate the ice load from the car wall and to permit the free flow of air about the ice and through the ducts so formed.

A further object of the invention is to provide a hatch ventilator which serves as a collector of any rain or air-borne dirt blown into the car through the open hatches and will direct any water so collected to suitable drains and away from the lading with which it would normally come into contact.

Other objects, advantages and capabilities of the invention will appear from the following description of a preferred embodiment thereof, taken in conjunction with the accompanying drawings, in which:

25 Figure 1 is a longitudinal sectional elevation of one end of a refrigerator car equipped with a convertible bulkhead and with the hatch closed and the hatch ventilator in collapsed position to form one wall of the collapsible ice bunker.

30 Fig. 2 is a fragmentary sectional elevation of the same end of a refrigerator car with the hatch open, the convertible bulkhead in retracted position, and the hatch ventilator in extended position beneath the hatch.

35 Fig. 3 is a transverse sectional elevation of a portion of the same end of the refrigerator car taken on the line 3—3 of Fig. 1, with the hatch ventilator in retracted position against the side wall of the car.

40 Fig. 4 is a fragmentary sectional elevation taken on the line 4—4 of Fig. 1 of the upper portion of the car with the bulkhead in extended position, showing the trough by which foreign matter collected in the hatch ventilator tray is carried away from the lading to the side of the car.

45 Referring to the drawings, the reference numeral 10 indicates the end wall of a refrigerator car composed of the conventional outer wall 11, inner sheathing 12 and interposed insulation 13. The end wall 10 is supported upon conventional structural members, such as the transverse sill 14 and the longitudinal sill 15. The roof of the car 16 is of conventional construction with the roof deck 17 separated from the ceiling 18 by

an air space 19, which may suitably be filled with an insulating material. The roof is supported by the transverse frame member 20.

At each end of the car and on both sides of the roof, openings or hatches 21 are made within the roof to give access to the ice compartment within the car for loading ice into the car and to provide for a means for ventilating the car when the car is used without ice and operated merely as a ventilated car. The hatch 21 is closed by the hatch cover 22. Only one hatch is shown on the drawings. Another hatch is normally provided on the other side of the car and a similar pair of hatches at the other end of the car.

The floor of the car 23 is of suitable sturdy construction with conventional structural members supporting the floor such as the longitudinal sill 15 supporting the transverse lower floor planks 24 and the upper floor planks 25, between which a suitable insulating filler 26 is interposed. Above the upper floor planks 25 is maintained the main floor rack 27, normally removable for cleaning, which is composed of longitudinal stringers 28, which run the length of the body of the car, and transverse planks 29. The planks 29 are separated from each other by crevices to form a rack upon which the lading within the car may be supported, but which will nevertheless permit the passage of the current of air passing along the floor of the car through the fissures between the planks and through the lading.

The description this far has been of conventional refrigerator car construction. The collapsible ice bunker with which the car is equipped forms the subject matter of my pending application, Serial No. 316,703. It comprises the ice bunker floor rack A shown retracted against the car wall in Fig. 1; the ice grates B and C, the first of which is shown in extended position and the second in collapsed position in Fig. 1; the permanent base D for the convertible bulkhead shown in section in Fig. 1; and the convertible bulkhead E which is shown in extended position in Fig. 1, and a fragment of which is shown in retracted position in Fig. 2.

The hatch ventilator F of this invention also forms part of the collapsible ice bunker, serving, when in collapsed position, as one of the walls of the ice bunker and providing ducts along the car walls for the circulation of cooled air, and when in extended position forming an improved pilfer-proof closure for the hatch opening 21 and a protection against injury to the lading from rain or any foreign objects that might enter the car through the hatch opening.

Before proceeding with the description of the hatch ventilator, the other elements of the collapsible ice bunker will be briefly described.

The collapsible ice bunker

The ice bunker floor rack A is shown in retracted position against the side wall of the car in Fig. 1. In lowered position it forms an extension of the refrigerator car floor rack 27.

Two of these floor racks A are preferably used at each end of the car, one reaching from the side of the car to the middle thereof, the other reaching from the opposed side to the middle, thus increasing the facility with which they may be swung into and out of position. Only one rack is shown.

Each floor rack A is pivotally mounted to the side wall 30 of the refrigerator car by the hinges 75

31 which may be of any number adequate to support the floor rack and the lading which it is designed to sustain. The floor rack is composed of the longitudinal channel beams 32 and the transverse floor members 33. These transverse floor members are shown in the form of inverted channels mounted in spaced relation to provide space for the free passage of air through the floor and the lading borne thereby.

10 Beneath the longitudinal channel beams 32 is mounted a grid 34. This grid is designed to provide a perforated wall of the ice bunker when the floor rack A is folded against the side of the car, both to separate the ice load from the 15 wall of the car and to permit free circulation of air along the car walls and through the interstices of the grid against which the ice is piled.

When the floor rack is in lowered position, the free sides rest upon the aprons 35 upon the 20 bulkhead support D, and the transverse ledge 36 formed upon the beam 37 at the end of the car, forming a continuation of the floor rack 27. This renders the end of the car available for 25 lading without the intervention of any obstacles or variation in the floor level. The construction is such that air may readily pass through this collapsible floor rack to permit ventilation of the lading and to present no obstacle to the free 30 passage of the air along the floor of the car and through the permanent floor rack 27 in the body of the car.

The refrigerator car is provided with suitable latches not shown secured to the side walls of the car which engage the end of the floor rack to hold it in vertical position as shown in Fig. 1.

The collapsible ice bunker is provided with two ice grates, the lower one of which is marked "B" and the upper one "C." These grates are 40 of substantially identical construction and are therefore described together. The lower ice grate is shown in extended position and the upper one in retracted condition swung into vertical position against the end wall of the car in Fig. 1.

The mounting of grates at two levels is designed to permit the loading of ice into the upper half of the ice bunker when less than a full bunker of ice is used. Frequently, the distance to be traveled or the weather conditions encountered enable the car to be refrigerated with a small quantity of ice, and as most efficient cooling is effected by having the ice near the top of the refrigerating compartment, the upper grate C is provided to receive the ice load at such times. The grate C also serves as a horizontal support for the convertible bulkhead E when in extended position.

The ice grates are formed of the longitudinal frame members 38 with suitable intermediate longitudinal bars and transverse grate bars (not shown). Each of the frame members 38 is pivotally secured to the end of the car upon a pivot 39 mounted within the duct 40. Thus, when the frame members 38 are swung into vertical position they may be maintained entirely upright and leave a substantial distance between the surface of the grates B and C and the actual wall of the car.

Each of the longitudinal frame members 38 is notched at its outer end to engage a horizontal bolt 42 secured to the convertible bulkhead E. The grate bars thus form horizontal supports for the bulkhead E which may be readily disengaged when the bulkhead is to be re-

tracted. To secure the grates B and C in vertical position when the ice bunker is collapsed, suitable latches may be provided.

Secured to the floor of the car is the transverse member D shown in transverse section in Fig. 1, which forms the permanent base for the convertible bulkhead when in extended position. It is composed of several pedestals 43 secured to the floor of the refrigerator car, supporting a beam 44 which runs almost the entire width of the car and is secured to the several respective pedestals 43. The beam 44 supports the bulkhead wall E when in extended position and the pedestals 43 are formed to provide the aprons 35 which form supports for the longitudinal members 32 of the collapsible floor rack A.

The convertible bulkhead E is composed of a number of vertical beams 45, which form a vertical frame work for the planking 46 which forms the bulkhead proper.

The bulkhead is hollow and has an inner metal wall 47 spaced from the planking 46 by the vertical beams 45, and perforated to permit ready circulation of air from the ice bunker into the ducts formed in the bulkhead between the planking and the inner wall.

To permit a flow of the air current from the lading into the ice bunker, the bulkhead planking 46 is not extended from the bottom of the bulkhead to the ceiling, but stops a foot or two from the ceiling, where the inner bulkhead wall 47 is slotted and screened as shown at 47.

The bulkhead E is movably suspended from the side walls of the car by means of the wheels 48 carried by the beams 45 and which ride on the tracks 49 secured to the inner sheathing of the side wall of the car. It also rides upon the lower wheels 50 which are borne by the longitudinal beams 32 on the floor rack.

The top edge of the bulkhead is reinforced with a channel beam 51, which extends the full length of the bulkhead and provides a sturdy member by which the upper part of the bulkhead can be firmly held when the bulkhead is in extended position. This channel beam is held between the legs of short sections of H-beam 52 which swing upon pivots within the ceiling of the car.

The grate bars 38 of ice grates B and C, when swung into horizontal position with their keepers engaging the horizontal bolts 42 form firm structural units to maintain the bulkhead in vertical position and to sustain the bulkhead against the thrust and shocks of the ice load within the bunkers as the car travels.

To maintain the convertible bulkhead E in retracted position against the end wall of the car, a pivoted detent 53 is provided. This detent is pivoted at its outer end and its free end will swing into the path of the wheel and prevent movement of the wheel and suspended bulkhead.

Secured to the vertical supports 45 of the bulkhead is the transverse trough 54, which extends across the full width of the car. This trough is an important part of the hatch ventilator and cooperates therewith to protect the lading in the car from rain and dirt.

The hatch ventilator F

In Fig. 1 the hatch F is shown swung down against the side wall of the car, a position which it occupies when the car is used as an ice-refrigerated car. In Fig. 3 the member F is shown

in the same position in section. In Fig. 2 the member is shown in a horizontal position, swung across and under the car hatch, a position in which the hatch ventilator is supported when the car is used as a ventilated car.

The hatch ventilator F is composed of a flat hollow structure made up of the foraminous grid 55, secured to the channel beams 56, 57 and 58 which give the member rigidity and form the frame members for the hatch ventilator. In place of the grid 55 the upper surface of the ventilator may be formed of a plate perforated at frequent intervals, to provide for the entry of air into the car when the hatch ventilator is closed and the hatch cover 22 open.

The upper grid or surface plate 55 is also cut with suitable openings 59 and 60 to provide toe and hand holds for entry into and climbing from the ice bunker.

The intermediate beam 57 and the beam 58 are preferably perforated with a series of openings 61 as shown in Fig. 3 to permit free passage of air into the car when the hatch ventilator is in closed position.

Beneath and secured to the beams 56 and 57 is the hatch ventilator drain plate 62. This plate is solid throughout the area underlying the hatch opening 21 and for substantial margins beyond that area. The plate is flanged at its inner edge with the flange 63, and at its outer edge with the flange 64. The beam 56 forms a wall along the third edge of the plate. The plate is made so that the fourth edge does not reach the beam 58, but provides a slot 65 over the trough 54 when the bulkhead is retracted, as shown in Fig. 2. The plate can be extended to the beam 58 and suitable holes or slots for drainage provided over the trough 54.

At one end of the hatch ventilator F it is pivotally secured to the side wall 39 of the car by means of the hinges 66, the knuckles of which are fastened to the car side wall and the straps to the hatch ventilator F as best shown in Figs. 1 and 3. The sliding bolt 67, which can be manipulated only from within the car, engages the adjacent beam suspended from the car ceiling to lock the hatch ventilator in horizontal position.

When the hatch ventilator is locked in horizontal position, and the hatch cover 22 held in raised position by means of hatch cover bracket 68 and hatch cover lever 69, the perforations through the grid 55 and the channel beams 57 and 58, and the slot 65, permit the free passage of air through the ventilator and into the car for the purpose of ventilation. A suitable lock 70 is provided to lock the hatch cover in closed position, or it may be locked by passing a padlock through bracket 68 and lever 69.

When the hatch ventilator F is folded down against the side wall of the car as shown in Figs. 1 and 3, when the car is to be used for ice refrigeration, the perforations in the grid or channel beams permit the ready passage of air through the ice and through the convection ducts formed within the hatch ventilator and by the other structural elements of the convertible bunker and through the car. The grid 55 is spaced from the car wall by the channel beams 56, 57 and 58, and thus forms ducts between the drain plate 62, which lies against the side wall of the car, and the ice with which the collapsible bunker may be filled. The hatch closure F thus serves, when in lowered position, as a convection

duct and as one of the walls of the ice compartment.

In order to secure the hatch ventilator F in vertical position when swung down as shown in Figs. 1 and 3, offset feet 74 may be mounted at the free end of the hatch ventilator to underlie the free end of the floor rack A. When the latter member is latched in vertical position, the hatch ventilator is similarly restrained.

If the hatch ventilator is used on a car which is not designed for ice refrigeration, and is therefore not relied upon to serve as part of the ice bunker wall and to provide convection ducts along the car wall when swung into inactive position along the car wall, the grid 55 may be omitted from the structure.

Operation of the hatch ventilator

If the car is in use as an ice refrigerated car with a full load of ice in the bunker, the respective elements of the convertible bunker will be in the respective positions shown in Fig. 1, the floor rack A in vertical position against the wall, the bulkhead E in advanced position, the lower ice grate B in horizontal position to support the ice load, and the upper ice grate C swung into vertical position against the wall. The hatch ventilator will be swung into vertical position against the car wall above the floor rack A.

Air circulates within the car by convection, the warm air passing through the top of the bulkhead into the ice bunker, where it is cooled. The cooled air passes down the ducts formed along the car side walls by the floor rack and hatch ventilator, the end wall by the screen 41, and in the bulkhead by the inner wall 47.

When the car is changed from an ice refrigerated car to a ventilated car, the hatch cover 22 is opened, the ice grate B swung into vertical position, the floor rack A and the hatch ventilator F swung into horizontal position, and the bulkhead E rolled against the end of the car. The hatch cover can be secured in open position by the bracket 69 and lever 69 for ventilation.

With the parts in this position, the drain plate 62 will underlie the hatch but nevertheless leave openings for free circulation of air into the car.

Air entering the hatch passes freely through the hatch opening 21, the hatch ventilator grid 55, the perforations 61 in the beams 57 and 58, the slot 65, and the ducts in the bulkhead, as well as over the flanges 63 and 64 on the drain plate 62.

The principal opening for the passage of the air is the slot 65 through which the air is directed into the ducts formed by the bulkhead E which direct the stream of air to the floor of the car. From the floor of the car it passes upwardly through the rack 21 and the fissures between the transverse planks 29 upon which the lading in the car is borne.

Any rain or dirt that is carried into the hatch strikes the drain plate 62 and, if in sufficient quantities, flows over the plate through the slot 65 into the trough 54, by which it is directed along the car walls to the pocket below the floor rack A. Refrigerator cars are normally provided with drains in the car floor through which the water and dirt escape from the car.

The flanges upon the drain plate 62 prevent any rain or dirt entering the car over the lading and thus protect the lading against damage.

Although the invention has been disclosed in connection with the specific details of a preferred embodiment thereof, it is to be understood that such details are not intended to be limitative of the invention except insofar as set forth in the accompanying claims.

Having described this invention, what I claim as new and desire to secure by Letters Patent is:

1. A hatch ventilator for a refrigerator car having a ventilating opening in its top comprising a drain plate adapted to underlie the opening with its edges spaced from the side walls of the car, the drain plate having upstanding flange members around its periphery to retain water thereon and formed with openings therethrough above the plate to permit the flow of air from the ventilating opening through the last named openings around the drain plate, means pivotally connecting the drain plate to a wall of the car so it can be swung into a vertical position along one wall of the car or into a horizontal position below the ventilating opening, the drain plate being formed adjacent one end with a drain opening, and a trough mounted in the car to register with the drain opening when the drain plate is in its horizontal position.
2. A hatch ventilator for a refrigerator car having a ventilating opening in its top comprising a drain plate adapted to underlie the opening with its edges spaced from the side walls of the car, the drain plate having upstanding flange members around its periphery to retain water thereon and formed with openings therethrough above the plate to permit the flow of air from the ventilating opening through the last named openings around the drain plate, means pivotally connecting the drain plate to a wall of the car so it can be swung into a vertical position along one wall of the car or into a horizontal position below the ventilating opening, the drain plate being formed adjacent one end with a drain opening, and means in the car to register with the drain opening when the drain plate is in its horizontal position to conduct any water flowing through the drain opening along a wall of the car.
3. A hatch ventilator for a refrigerator car having a ventilating opening in its top comprising a drain plate adapted to underlie the opening with its edges spaced from the side walls of the car, the drain plate having upstanding flange members around its periphery to retain water thereon and formed with openings therethrough above the plate to permit the flow of air from the ventilating opening through the last named openings around the drain plate, a perforated cover member secured to the upper edges of the flange members to lie against the car top in register with the ventilating opening means pivotally connecting the drain plate to a wall of the car so it can be swung into vertical position along one wall of the car or into horizontal position below the ventilating opening.

JOHN S. LUNDVALL
